(57) CLAIM

The ornamental design for a plug body for drink container, as shown and described.

DESCRIPTION

FIG. 1 is a perspective view from above of a plug body for drink container, showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken lines are for illustrative purposes only and form no part of the claimed design.
